UNITED STATES PATENT OFFICE.

FRED LUCKING, OF PHILADELPHIA, PENNSYLVANIA, ASSIGNOR TO THE NATIONAL SOCIETY OF THE CHILDREN OF THE AMERICAN REVOLUTION.

DESIGN FOR A BADGE.

SPECIFICATION forming part of Design No. 25,452, dated May 5, 1896.

Application filed April 4, 1896. Serial No. 586,265. Term of patent 14 years.

To all whom it may concern:

Be it known that I, FRED LUCKING, a citizen of the United States, residing at Philadelphia, State of Pennsylvania, have invented and produced a new and original Design for Badges or Insignia, of which the following is a specification, reference being had to the accompanying drawing.

- 10 The leading or characteristic features of my design consist of a circular panel or band with a buckle upon its lower border, the open surface within said band, at or near the center, having across the face thereof the representation of a flag showing a field of thirteen stars, the remainder of the flag being folded across the staff, and the end of the flag extending below the lower rim of the band. The staff lies diagonally across the opening of the circle or
- 15 band, the ends of the staff extending beyond
- 20

the outer rim of the circle. From above the flag, within the circle, rise the neck, head, and wings of an eagle, its claws grasping the staff of the flag, its beak open, the tips of its extended wings reaching beyond the upper border of the circular band, and its tail appearing below the flag upon the lower chord of the circle.

a represents the circular band. *b* represents the flag. *c* represents the eagle.

The panel upon the circular band affords space for suitable inscription.

What I claim, and desire to secure, is—
The design for a badge herein shown and described.

FRED LUCKING.
